UNITED STATES PATENT OFFICE.

JOHN HOARE, OF CORNING, NEW YORK.

DESIGN FOR THE ORNAMENTATION OF GLASS OR OTHER WARE.

SPECIFICATION forming part of Design No. 20,504, dated February 3, 1891.

Application filed December 13, 1890. Serial No. 374,652. Term of patent 7 years.

To all whom it may concern:

Be it known that I, JOHN HOARE, a citizen of the United States, residing at Corning, in the county of Steuben and State of New York, ⁵ have invented and produced a new and original Design for the Ornamentation of Glass and other Ware, of which the following is a specification, reference being had to the accompanying drawings, forming part thereof, ¹⁰ in which—

Figure I shows my design projected, and Fig. II is a side elevation of a bowl having my design applied thereto.

The leading features of my design consist ¹⁵ in a series of links or rings and two serpentine strips or bands extending around the wall of the bowl, the bands or strips being interlaced with the links or rings, one strip or band passing over one link or ring and under the next ²⁰ link or ring, or vice versa, and the other strip or band passing under the link or ring and over the next link, or vice versa.

1 are a series of links or rings extending around the wall of the article and of nearly the height thereof.

2 are two serpentine strips or bands, also

extending around the wall, interlaced with the links or rings and reaching from the bottom to a point near the top of the article and crossed and linked together within the links ³⁰ or rings, one strip or band passing in front and the other strip or band to the rear of a link or ring, so that the portion of a strip or band extending in front of a link or ring passes behind the strip or band extending to the rear ³⁵ of the link or ring. The links or rings are shown as bounded by deep cuts 3.

Fan figures 4 are seen in the spaces produced by the design.

The links or rings and strips or bands may ⁴⁰ be decorated in any manner.

Having thus described my invention, the following is what I claim as new therein and desire to secure by Design Letters Patent:

The design for the ornamentation of glass ⁴⁵ and other ware, substantially as herein shown and described.

JOHN HOARE.
